(57) CLAIM

We claim the ornamental design for a wipes package and dispenser, as shown and described.

DESCRIPTION

FIG. 1 is a wipes package and dispenser showing our new design.

FIG. 2 is a front view thereof.

FIG. 3 is a back view thereof.

FIG. 4 is a left side view thereof.

FIG. 5 is a right side view thereof.

FIG. 6 is a top view thereof.

FIG. 7 is a bottom view thereof.

FIG. 8 is a perspective view thereof with the wipes package shown in an opened position; and,

FIG. 9 is an additional perspective view thereof.

The broken line showing of the wipes package and dispenser is for illustrative purposes only and forms no part of the claimed design.
